CONTAINER FOR PACKAGING AND INFLATING PNEUMATIC ARTICLES**Elliott D. Harrowe, Hollis, N.Y., assignor to Ideal Toy Corporation, Hollis, N.Y., a corporation of New York****Application November 6, 1953, Serial No. 390,615****2 Claims. (Cl. 206—47)**

This invention relates generally to containers, and is particularly directed to novel containers for pneumatic articles.

Heretofore, as is well known to those in the industry, the popular acceptance of numerous types of pneumatic articles has been inhibited by certain inherent difficulties. For example, in the case of plastic wading and swimming pools for domestic use, a problem exists in the lack of simple and convenient inflating means. The practice of oral inflation is unsatisfactory for obvious reasons, while the use of conventional bicycle pumps has proved ineffective for want of capacity and adaptability. Further, the difficulty of transporting such pneumatic devices in their inflated condition prohibits the use of relatively distant air pressure sources.

Another heretofore existent problem in the mass distribution of pneumatic devices was the necessity for relatively expensive protective packaging during transportation and storage, both before and after sale to the ultimate consumer. As inflatable devices are usually fabricated of relatively fragile, sheet material, and have little or no rigidity in their deflated condition, it was necessary to employ relatively staunch, and consequently expensive, containers to assure protection against abusive handling.

Accordingly, it is a principal object of the present invention to provide simple and efficient means for packaging and inflating pneumatic articles so as to adequately protect the same during transportation and storage, and permit of quick, easy and convenient inflation without the use of auxiliary devices.

It is another object of the present invention to provide a novel and inexpensive container for pneumatic articles, which is rigid and durable to afford long lasting protection, which is variable in size to accommodate a wide variety of articles, and which is capable of effecting the transfer of fluid under pressure into such pneumatic articles to distend and inflate the same.

It is another object of the present invention to provide a combination device for containing and inflating a pneumatic article, which device includes novel and improved features of construction permitting of attachment to a pneumatic article of inflating the same.

Other objects of the present invention will become apparent upon reading the following specification and referring to the accompanying drawings, which form a material part of this disclosure.

The invention accordingly consists in the features of construction, combinations of elements, and arrangement of parts, which will be exemplified in the construction hereinafter described, and of which the scope will be indicated by the appended claims.

In the drawings:

Fig. 1 is a side elevational view, partly broken away, showing a device constructed in accordance with the present invention and a deflated, pneumatic article contained therein;

Fig. 2 is a perspective view showing a pneumatic wad-

ing pool in inflated condition, the inflating means of the present invention being illustrated schematically in broken outline;

Fig. 3 is a greatly enlarged side elevational view illustrating in detail a device constructed in accordance with the present invention, the device being partially broken away for clarity of understanding;

Fig. 4 is a sectional view taken substantially along the line 4—4 of Fig. 3;

Fig. 5 is a sectional view taken substantially along the line 5—5 of Fig. 3;

Fig. 6 is a bottom plan view of the device as shown in Fig. 3;

Fig. 7 is an enlarged view, partly in section, showing a valve or closure element of the pneumatic device adapted for use with the present invention; and

Fig. 8 is an enlarged, fragmentary sectional view showing the combination device of the present invention, and a fluid communication with each other, the valve being shown in broken outline in its closed position.

Referring now more particularly to the drawings, the embodiment of the invention illustrated therein comprises a container, generally designated 10, and a pneumatic article 35 in deflated, folded condition and disposed within the container 10.

The container 10 includes a generally cylindrical or tubular member 11 having one end open, as at 12, and having the other end closed by a closure or plate 13. The closure plate 13 is formed with a plurality of eccentric apertures or openings 14, and further provided with an inwardly extending open ended tubular member or sleeve 15 which has its opposite ends opening into the interior and exterior of the cylindrical section 11 for fluid communication therebetween. On the inner end of the sleeve 15 is formed an outstanding annular lip or flange 16, for a purpose which will appear presently. A flexible, resilient sheet 17, which may be fabricated of rubber or other suitable material, is circumposed about the sleeve 15 and preferably adhesively secured to the inner surface of the plate 13. The sheet 17 is arranged with an outer portion or flap 18 freely overlying and closing the apertures 14. More particularly, the flap 18 is normally in covering or closing relation with respect to the apertures 14 and is movable inwardly under fluid pressure to the dotted line position for opening the aperture. It will now be apparent that the flap 18 and apertures 14 combine to provide a one way valve communicating between the interior and exterior of the cylinder 11 to permit ingress of fluid through the aperture and prevent egress of fluid therethrough.

Snugly circumposed about the sleeve 15 is the bottom wall of an upwardly opening cup-shaped member 20, which is held in position on the sleeve by the upset flange or lip 16. An outstanding bead or ridge 21 extends circumferentially about the cup-shaped member 20, spaced below the upper edge thereof; and, a downwardly facing or inverted complementary cup-shaped member 22 is snugly circumposed about the member 20 and has its lower edge in abutting engagement with the bead 21. Formed in the top wall 23 of the inverted cup-shaped member 22 is an eccentrically disposed, through aperture 24. A flexible resilient sheet 25 is secured in facing engagement with the undersurface of the wall 23, preferably by adhesive means, and has an outer portion or flap 26 normally disposed in covering or closing relation with respect to the aperture 24. The flap 26 is movable to the position shown in Fig. 3 under the influence of fluid pressure within the cylinder 11 to open the aperture 24 and permit the passage of fluid through such aperture and out of the cylinder through the sleeve 15. Hence, the complementary cup-shaped members 20 and 22 combine to form a housing; and, the flap 26, movable

within the housing, cooperates with the aperture 24 to provide a one way valve which permits the egress of fluid from the member 11 and preventing the entry of fluid therein.

A second tubular member or cylinder 27 is arranged in telescopic relation with respect to the cylinder 11 and has its distal end closed by a plate 28, its proximal end 29 remaining open. That is, the cylindrical section 27 has its open end 29 extending slidably inwardly through the open end 12 of the cylinder 11. Secured on the outer face of the closure plate 28 is a loop or handle 30 for purposes which will soon become apparent.

It will now be understood that the tubular members 11 and 27, and their respective end closures 13 and 28 combine to form a substantially fluid-tight chamber, which is of a variable size dependent upon the relative positions of the tubular members. Further, the member 27 is readily slidable in the member 11 to expand and contract the container 10; and, as the flap 18 permits the ingress of fluid upon expansion and the flap 26 permits the egress of fluid upon contraction, only slight back pressure is experienced. In practice, it has been found that close tolerance between the cylinders is unnecessary, so that cylinders fabricated of stiff cardboard or the like will function quite satisfactorily.

In Fig. 2, for purposes of illustration, the pneumatic article 35 is shown as a wading pool, but it is appreciated that a wide variety of pneumatic articles are equally well adapted for use with the present invention. In order to inflate the pool 35, it is necessary to provide means for connection to a source of fluid supply. In Fig. 8 such a connection means is shown, wherein a relatively firm, but slightly yieldable plug 36 is formed with a through bore or hollow 37 and secured to the pool 35 so as to communicate between the interior and exterior thereof. A hollow tubular valve or closure member 38 is slidable in the plug 36 and extends beyond the opposite ends of the latter. Formed on the outer end of the closure 38 is a knurled flange or shoulder 39 which abuts the plug to limit inward movement of the valve; and, the inner end of the hollow valve member 38 is closed by a plate 40 which extends laterally to form a shoulder or edge portion 41 engageable with the inner end of the plug 36 to limit outward movement of the valve member. The valve member 38 is formed with side openings 42 adjacent to and spaced from the end plate 40 and communicating between the interior and exterior of the valve member. As seen in Fig. 8, the apertures 42 are disposed interiorly of the pneumatic article 35 when the valve element 38 is in its inward position of movement, so that fluid communication exists between the interior and exterior of the pneumatic article through the openings 42 and interior of the valve element. When the valve element 38 is moved to its outward position, shown in broken outline, the openings 42 will be disposed within the plug 36 and closed thereby to prevent fluid communication between the interior and exterior of the pool.

As seen in Fig. 1, the pool 35 may be deflated and folded to occupy a relatively small space, in which condition it may be completely and conformably enclosed within the container 10. More particularly, the tubular members 27 and 11 may be separated for reception of the pneumatic article, and then replaced in their telescopic relation. Further, it will now be understood that the container 10 may be adjusted by relative sliding of the members 27 and 11 to conformably enclose pneumatic articles of different sizes, so that containers of equal dimensions constructed in accordance with the present invention may be employed for snugly enclosing articles of varying size. Of course, removal of the pneumatic

article may be effected by reversing the above described procedure.

When it is desired to inflate the pool 35, after its removal from the container 10, the valve element 38 is moved to its inward position, and the plug 36 and valve element are inserted into and frictionally engaged in the sleeve 15, as illustrated in Fig. 8. It is then only necessary to reciprocate the tubular member 27 relative to the tubular member 11, as by manual actuation of the handle 30, to effect the passage of fluid under pressure into the pneumatic article. More particularly, withdrawal of the tubular member 27 in the direction of the broken arrow serves to expand the container and draw fluid inwardly through the aperture 14; and, movement of the tubular member 27 in the direction of the solid arrow serves to close the flap 18, open the flap 26 and permit the passage of fluid through the aperture 24, and the sleeve 15 into the pneumatic article. Flow of fluid from the pneumatic article to the container 10 is prevented by automatic closure of the flap 26 under fluid pressure. When the pool has been sufficiently inflated or distended, the plug 36 is withdrawn from the sleeve 15, which action automatically moves the valve element 38 to its outer position and closes the apertures 42. Thus, it is now seen that the structural elements of the container 10 cooperate to provide a simple and efficient means for inflating the pneumatic article 35, as well as to provide a durable and protective container for transportation and storage of the pneumatic article.

It will also be noted that the loop 30 may serve as a carrying handle when the pneumatic article is disposed within the container 10, as expansion of the container and separation of the members 11 and 27 is prevented by closure of the aperture 14. That is, the pneumatic article in its folded condition will rest upon the flap 18 to close the aperture 14 so that fluid will not be admitted into the container and expansion thereof will be prevented.

From the foregoing, it is seen that the present invention provides a device which fully accomplishes the intended objects, and which is well adapted to meet practical conditions of use.

Although the present invention has been described in some detail by way of illustration and example for purposes of clarity and understanding, it is understood that certain changes and modifications may be made within the spirit of the invention and scope of the appended claims.

What is claimed is:

1. In a variable size packaging device, a container comprising a pair of telescopic members of substantially equal length, said members having their distal ends closed and their proximal ends open to form a telescopic chamber, inlet means in the end of one of said sections, means in said telescopic chamber forming an outlet chamber and having an aperture defined therein to provide communication between said telescopic and outlet chambers, outlet means in said one end communicating with said outlet chamber, and valve means cooperating with said outlet chamber and operable in response to the expansion of said telescopic chamber to block said communication by way of said aperture and to permit said communication by way of said aperture in response to the contraction of said telescopic chamber.

2. In a packaging device as in claim 1, said telescopic members being separable to permit articles to be inserted and removed therefrom.
